SHIELD FOR WALL MOLDINGS

Charles F. Kirby, Berkeley, Calif.

Application April 9, 1940, Serial No. 328,718

3 Claims. (Cl. 91—65)

The invention relates to a shield or mask for temporary use to protect a molding installed on a wall from the accidental deposit on the molding of material which is being applied to a wall portion or ceiling immediately adjacent the molding.

An object of the invention is to provide a molding shield of particularly simple and effective structure and form.

Another object is to provide a molding shield which may be mounted on horizontally installed moldings without requiring the use of special securing devices.

The invention possesses other objects and features of advantage, some of which, with the foregoing, will be set forth or be apparent in the following description of a typical embodiment thereof, and in the accompanying drawing, in which.

Figure 1 is a fragmentary perspective view showing installations of the shield of my invention to protect the picture molding of a room side wall.

Figure 2 is an enlarged fragmentary perspective showing the present shield disposed for hanging support on a picture mold having a hook-receiving top bear portion.

Figure 3 is an enlarged fragmentary perspective showing the shield as engaged in operative relation with a square-cornered molding.

As particularly shown in Figure 1, shields or masks 5 embodying my invention are operatively disposed on and with respect to a usual picture molding 6 which is mounted in horizontal disposition on coterminous and flat side walls 7 and 8 which extend to the top wall or ceiling 9 of a room. The molding 6 has a more or less triangular cross-section and includes a cylindric top bead portion 6' for the mounted engagement thereover of a usual picture-hanging hook (not shown). As is a common present practice, the molding 6 is relatively close to the ceiling 9.

Each shield 5 is shaped from a strip of sheet material to have opposite edge portions 11 and 12 extend fixedly from a flat intermediate portion 13 of rectangular outline to provide a structure of uniform and somewhat Z-shaped cross-section. The portion 11 is cylindrically curved about an axis extending longitudinally of the shield to provide a cylindrically concave trough for complementarily receiving the molding bead 6' while the portion 13 lies opposite the outer face of the molding 6, and the portion 12 extends outwardly with respect to the molding and wall. The shield may be of any convenient length—

three feet, for instance—and is moved along a molding being protected as the work adjacent thereto progresses.

When a shield has its part 11 hooked over a molding in the manner disclosed in Figures 1 and 2, it protects the top and front of the molding from the accidental deposit thereon of a more or less liquid material with which the wall or ceiling portion above the molding and shield is being treated by brushing on or spraying a paint, calcimine, glue sizing, paper-securing paste, crack filler, wall cleaning material, etc. While valuable for general use, the present shield is particularly useful while working on a side wall portion above a molding which is relatively close to a ceiling, as is illustrated.

It will be noted that material deposited on the shield portions 11 and 13 and moving downwardly along the outer faces thereof is held against dripping from the bottom edge of the unit by reason of the outward extension of the portion 12 which is cooperative with the portion 13 to provide what may be termed a drip-catching shelf or trough for protecting the wall portion beneath the unit. In connection with the latter feature, it will be understood that the present shield unit may satisfactorily protect and more or less secure the upper edge of a drop cloth (not shown) which is applied between the molding and unit for protecting the molding and the wall beneath it.

In the case where a supporting molding has a flat upper edge which is substantially perpendicular to the supporting wall, a shield 6 may be turned over and applied as in Figure 3, with the portion 12 engaging the top of a molding 14 while the trough of the portion 11 may then function as a drip shelf or trough with respect to the other portions. The portion 12 has its outer part turned inwardly upon itself for providing a stiffening bead 12' for the unit thereat, and said bead provides for a downward sloping of the top face of the portion 12 from the wall when the unit is operatively mounted, whereby to insure an outward flow of any flowable material deposited on the portion.

The molding 14 may be a picture mold, a plate rail, a casing for a wall opening, or some other horizontally disposed wall element having a flat top edge. In the present instance, the molding 14 is disclosed as comprising the head casing for an opening in the wall 8 below the line of the molding 6; while said wall opening may be that for a window or be left open, it is particularly shown as being closed by a door 15.

When a present shield unit is mounted on a

molding 6 or 14, it will be gravitally held in place. The shield may, however, be used for its protective or masking purposes at the sides of upright moldings or other elements of a wall. Thus, for example, the present shield may be operatively applied along the side casings 16 for the opening at the door 15, it being necessary only that it be manually or otherwise held in place during its use.

From the foregoing description taken in connection with the accompanying drawing, the advantages of the construction and operation of the present device will be readily understood by those skilled in the art to which this invention appertains. While I have described the features and principles of operation of a structure which I now consider to comprise a preferred embodiment of my invention, I desire to have it understood that the showing is primarily illustrative, and that such changes may be made, when desired, as fall within the scope of the following claims.

I claim:

1. A shield for protecting installed wall moldings while the adjacent wall portions are being treated, which comprises an elongated member of generally Z-shaped cross-section for complementarily receiving and engaging a molding portion within the lesser angle defined by the central shield portion and one of its flange portions, said

central shield portion and one flange portion being planar and the other flange portion being cylindrically concave at its inner face.

2. A shield for protecting a molding mounted horizontally on a wall while the adjacent wall portion is being treated up to the molding with a liquid preparation, which comprises an elongated member of generally Z-shaped cross section for installation to enclose upper and front face portions of the molding in the angle defined by its central portion and one of the flange portions with the flange portion engaging the upper molding edge as the sole support for the shield, and the other flange portion extending outwardly from the central portion to provide a drip-catching shelf.

3. A shield for temporarily protecting a molding on a wall face, comprising a unitary strip of sheet material of uniform angle section having one flange portion thereof arranged for masking disposal against a molding edge extending transversely from the wall while permitting free access to the wall portion extending from said molding edge, while the other flange is simultaneously disposed opposite the outer face of the mold as a masking means therefor, the extreme free edge of the first flange portion being provided with a uniform and inwardly projecting bead thereat.
